(57) **CLAIM**

The ornamental design for latch furniture, as shown and described.

DESCRIPTION

FIG. 1 is a perspective view of the latch furniture showing my new design;

FIG. 2 is a further perspective view thereof but showing the slide member at the other end of its travel;

FIG. 3 is a front elevation view thereof;

FIG. 4 is a back elevation view thereof;

FIG. 5 is a side elevation view thereof when viewed from the top of FIG. 3;

FIG. 6 is a side elevation view thereof;

FIG. 7 is an end elevation view thereof; and,

FIG. 8 is an end elevation view thereof when viewed from the right of FIG. 3.

The broken lines are for illustrative purpose only and form no part of the claimed design.
